UNITED STATES PATENT OFFICE

137,885

DESIGN FOR A LAMP

Henry Birsh, New York, N. Y.

Application February 1, 1944, Serial No. 112,470

Term of patent 14 years

(Cl. D48—20)

To all whom it may concern:

Be it known that I, Henry Birsh, a citizen of the United States, residing at New York city, in the county and State of New York, have invented a new, original, and ornamental Design for a Lamp, of which the following is a specification, reference being had to the accompanying drawing, forming part thereof.

The figure is an elevational view of a lamp showing my new design.

The characterizing features of my new design are shown in full lines on the drawing.

This application is a continuation-in-part of my prior application D110,239, filed May 19, 1943.

I claim:

The ornamental design for a lamp, as shown and described.

HENRY BIRSH.
